COMBINED QUARTZ MILL AND CRUSHER

Artist Mole, Fresno, Calif., assigner to Mole Quartz Mill Mfg. Co., Portland, Oreg., a corporation

Application October 22, 1931, Serial No. 570,481

2 Claims. (Cl. 83—13)

This invention relates to a combined quartz mill and crusher and aims to generally provide a construction which may operate at high speed and which will treat ore faster, and which will effect a greater percentage of saving in gold values with the use of less water, power, labor and expense generally.

It is further aimed to provide a construction of mill which may be made in any desired size and usually in several sizes to care for varying conditions, one which is designed for operation by one man, one which will eliminate heavy expense of freighting tons of steel to maintain tops and requiring weeks and months to install, and one which may be readily assembled and disassembled, easily cleaned, and is capable of use on level ground or on hillsides and may be driven from the top or bottom.

Various additional objects and advantages will become apparent from a consideration of the description following taken in connection with accompanying drawings illustrating an operative embodiment.

In said drawings:—

Figure 1 is a view in front elevation of the improved apparatus.

Figure 2 is a central vertical sectional view taken on the line 2—2 of Figure 1.

Figure 3 is a central vertical sectional view through the device of Figure 1 taken at a right angle to Figure 2.

Figure 4 is a sectional view taken on the line 4—4 of Figure 3.

Figure 5 is a sectional view taken on the line 5—5 of Figure 4.

Figure 6 is a plan view of the grinder head.

Figure 7 is an enlarged detail sectional view through the upper paper bearing for the shaft, and

Figure 8 is a sectional view taken on the line 8—8 of Figure 2.

Referring specifically to the drawings, 10 designates a foundation of approved form which may be of concrete or any other approved material, for instance formed in the shape of a ring and having a radial break or passage 11 through the wall thereof. Disposed on the foundation 10 is a reservoir or casing generally designated 12 which is surmounted by an upper section 13. Bolts 14 are anchored in the foundation 10 and pass through flanges 15 and a disk 16 of the section 13 receiving a nut 17 above the latter, and thus removably securing the casing 12 and section 13 together.

Integral with the section 13 is a flared portion 18 which constitutes a receiving hopper for the ore or quartz. The inner surface of the hopper 18 is roughened or burred as at 19, and the roughened portions or burrs progressively increase in size in an upward direction. Such burrs 19 coact

with burrs or projections 20 on a cone 21, burrs 20 also increasing in size progressively in an upward direction. Element 18 in view of the projections 19 constitute the burrs and it will be noted that it is arranged on a different cone from that at 21, so that the receiving space for the bore or port decreases progressively in a downward direction.

A suitable taper bearing construction 22 is removably disposed in the bore of the section 13 and a vertically disposed power shaft 24 is journaled in such bearing. The bearing 22 is provided with a removable screw cap 23 which compresses waste or other material 26 disposed within the bearing, against the shaft 24 and which waste is adapted to be saturated with lubricant and to form a dust proof joint with the shaft.

Above the bearing 22, shaft 24 removably carries the burr 21, the latter being fastened to the shaft as by means of a key 27 disposed in a longitudinal groove 28 in the shaft.

Fastened to the top of the hopper 18 by screws 29 is a spider 30 forming a central bearing 31 for the said shaft. Above the spider, a plurality of nuts 32, one of which serves as a lock nut, are screw threaded to the shaft 24 as shown, serving to secure the shaft and cone 21 thereon securely in different adjusted positions and to take up wear.

The power for operation may be acquired from any desired source and may be applied for instance to a pulley 33 keyed at 34 removably in the groove 28 to the shaft 24. Said shaft 24 passes also through the bottom wall 35 of the reservoir 12, such wall being relatively thick and having its upper surface inclining from the center downwardly and outwardly. At the wall 35, shaft 24 is journaled in a taper bearing construction 36 in a fluid tight manner and the latter is engaged by nuts 37, one of which locks the other, screw threaded as shown on the shaft 24 below the wall 35. Shaft 24 extends below the nuts 37 and has a groove 38 therein, so that if desired, the key 34 may be applied thereto and secure the pulley 33 to the lower end of the shaft, the belt driving element in such event entering through the space 11 previously referred to.

In order to lubricate the bearings 23 and 36, a groove 39 is provided longitudinally of the shaft 24 having outlets 40 and 41 at such bearings, respectively so that lubricant may be injected by means of a gun or the like into the groove 39 and thence through the ports 40 and 41 to the bearings proper.

Slightly spaced from and coacting with the under surface of the disk 13 is a grinding plate or member 42 which is keyed as at 43, detachably to the shaft 24. Such plate or grinding element 42 is vertically adjustable and is secured in its different positions by nuts 44, one of which locks

the other, and both of which are threaded on the shaft 24 as shown.

The upper surface of the grinding plate 42 has an auxiliary plate 42^a while the grinding plate or member 13 has an auxiliary plate 13^a on its lower surface. Plates 42^a and 13^a are preferably of hardened metal and made in four or any desired number of separate and removable sections as suggested in Figure 6, the sections being secured in place to the respective grinding members as by means of bolts 42^b and 13^b, respectively. Such plates or sections 13^a and 42^a preferably have integral ribs 42^c and 13^c thereon interfitted in grooves in the respective grinding plates.

The outer portions of the plates 13^a and 42^a are relatively close together but do not touch, being parallel and the space between such plates gradually increases inwardly toward the center, being about one-half an inch apart for example at the center and tapering gradually to a distance of substantially one-eighth of an inch substantially one-half way between the periphery and center, all abrupt shoulders being avoided. The central portions of each of the said plates 42^a and 13^a are dished to provide the necessary space but the plate 42^a is dished more than the other plate as is apparent in Figures 2 and 3. The surfaces of the plates 13^a and 42^a which face each other and which are adjacent the center, have grinding elements or teeth providing tangential grooves 43^a. Such grooves 43^a discharge into the unrestricted space between the parallel portions of the plates 42^a and 13^a. Marginally around the plate 42, a band 48 is fastened which extends into an annular undercut groove 47 in the under surface of the disk 13 outwardly of the plate 13^a.

The ore ground by and passing the burrs 21 and 18 enters the bore 49 of member 13 and from the latter passes through passages 50 in such member 13 which discharge into the grooves 43^a, the same being ground by the plate 42 and passing up over the flange 47 and thence downwardly into a space 52 provided between the side walls of the reservoir 12 and in a drum 53 within such reservoir, the wall of the drum inclining downwardly and outwardly so that the space 52 is wider at the bottom than at the top. The drum 53 may be secured in place by bolts 54 and interposed spacing sleeves 55 surround it. The pulp from the space 52 passes into a body of quicksilver 56 maintained in the lower portion of the reservoir. The gold extracted by the quicksilver must pass the drum 53 and thence upwardly into the reservoir 12 inwardly of the drum, the wall 35 having a channel at 57 to facilitate such passage.

The water accumulates in the reservoir 12 above the quicksilver and carries off the tailings to an amalgamator through one or more chutes 58 provided through the drum 53 and side wall of the reservoir 12. In order to deflect incoming pulp from the chutes 58 inverted V-shaped baffles 59 as best shown in Figure 5 are disposed above the chutes and fastened to the drum 53 and reservoir 12.

Agitators 60 are adapted to travel the grinder 42, and may be carried by standards or fittings 61 removably fastened to the grinder. Such agitators 60 are generally of plow shape and it will be noted from Figure 4 that they are arranged at different distances from the center of the shaft so that each will travel in a different path about the same.

To facilitate entrance of an operator into the device for purposes of inspection and repair, a doorway may be provided through the vertical wall of the reservoir 12 as at 62 which is normally closed by a suitably hinged and locked door 63, the latter preferably carrying a sealing gasket 64 of rubber or the like to engage the wall 62 and form a water-tight joint.

In order to clean out the interior of the reservoir, a drain opening 65 is provided through the wall 35 which is normally closed by a plate 66 bolted in place at 67 and having a gasket 68 interposed between the plate 66 and wall 35 to form a leak proof joint, such plate 66 being accessible through the plate 11.

According to the present invention, the burr 21 and grinder 42 are simultaneously operated at great speed upon the driving of pulley 33, which pulley may be rotated as shown in Figure 2 or arranged at the bottom of shaft or as preferred or conditions warrant. Either the dry or wet method of treating the quartz may be followed. The quartz or ore is ground by the teeth 20 and 19, then passed into the bore 49 and from the latter through passages 50 reach the grooves of the grinding plate 42. From the latter, the material passes over the plane portion 45, thence over flange 47 and into the space 52 and thence into the quicksilver 56, the tailings accumulating above the quicksilver and passing out through the chutes 58 as previously described.

Various changes may be resorted to provided they fall within the spirit and scope of the invention.

I claim as my invention:—

1. An apparatus of the class described having burrs to receive ore therebetween, a vertical shaft to rotate one of the burrs, a grinder to receive material passing the burrs, a disk relatively close to the grinder and coaxing therewith, one of said burrs being in the form of a hopper and integral with said disk, said disk having an annular undercut groove, said grinder having an upstanding flange disposed in the groove, and over which the ground material is discharged, a dust and water-proof bearing in said disk for the shaft, said disk having passageways therethrough outwardly of said bearing to conduct the ground material from the burrs to said grinder member, a reservoir into which said ground material discharges, the bottom wall of the reservoir on its inner surface inclining downwardly and outwardly, said shaft passing through said wall, and bearing means in said wall for said shaft, and agitators depending from the grinder member into the reservoir.

2. An apparatus of the class described comprising a foundation, bolts rising therefrom, a casing disposed on said foundation, an upper section disposed on said casing, said bolts passing through said casing and section, an upright shaft journaled in said casing and section, a bearing on the shaft adjustably disposed in the bottom wall of the casing, a grinder member within the casing carried by the shaft, means on the shaft to support and adjustably position the grinder member, a bearing for the shaft in said section, a hopper integral with said section having an inner burr surface, a burr coaxing with the burr surface carried by said shaft, said section having an enlarged bore and passages leading therefrom to convey ground quartz to the grinder member.
